UNITED STATES PATENT OFFICE.

GOROICHI SAGARA, OF ARMONA, CALIFORNIA.

TURNING-SIGNAL FOR VEHICLES.

1,288,211.

Specification of Letters Patent. Patented Dec. 17, 1918.

Application filed July 2, 1917. Serial No. 178,180.

To all whom it may concern:

Be it known that I, GOROICHI SAGARA, a citizen of the United States, residing at Armona, in the county of Kings and State of California, have invented certain new and useful Improvements in Turning-Signals for Vehicles; and I do declare the following to be a full, clear, and exact description of the invention, such as will enable others skilled in the art to which it appertains to make and use the same.

My invention relates to improvements in devices for indicating when vehicles are to turn in one direction or the other or when they are to be brought to a stand still or slowed down.

The object of the invention is to provide a device of the class described which may be simply and inexpensively manufactured and marketed, yet one which will be highly efficient and durable, and with this general object in view, the invention resides in the novel features of construction and unique combinations of parts to be hereinafter fully described and claimed, the descriptive matter being supplemented by the accompanying drawings which form a part of this specification and in which:

Figure 1 is the front elevation of a portion of an automobile showing the application of one of the improved signals;

Fig. 2 is a vertical section on substantially the plane of the line 2—2 of Fig. 1, showing an inner end elevation of the device;

Fig. 3 is a vertical section on the plane of the line 3—3 of Fig. 2 showing the lazy tong arm in collapsed position; and

Fig. 4 is a view similar to Fig. 3 showing the relation of parts when the arm is extended.

In the drawings above briefly described, the numeral 1 designates a suitable support which is preferably in the form of a flat vertically disposed casing open at its outer end and closed at its inner end by a suitable plate 2 having side flanges 3 between which the inner end of the casing is seated, the upper end of plate 2 being integrally or otherwise joined to the rear end of a hood 4, the latter being hinged at 5 to the top of the

casing 1 and serving to prevent the entrance of water, snow and the like into the casing through an opening which is provided in the top thereof for a purpose to appear. Any suitable means could well be employed for holding the plate 2 in closed position, but the flanges 3 will in most cases frictionally embrace the casing 1 for this purpose, it being intended that the plate in question shall be swung outwardly whenever required, in order that the operating parts of the device may be oiled or repaired should occasion so demand.

A lazy tong arm 7 is normally housed within the casing 1 but is adapted to be projected therefrom whenever the vehicle is to be turned in one direction or the other or brought to a standstill, the outer end of said arm 7 carrying a suitable electric light 8. A pair of current-conducting wires 9 lead to the lamp 8 and pass through eyes or other suitable guides 10 located at the outer ends and at the central pivots of the several links of which the arm 7 is constructed, this arrangement of guides serving to effectively hold the wires against becoming entangled as the arm is projected and retracted. It will of course be understood that a suitable switch will be employed for cutting off the current of the light 8, when the device is being used in the day time, whereas said switch may readily be closed at night. Also, should occasion demand, any of the well known circuit making and breaking devices, could well be used for closing the circuit of the light automatically when the arm is projected and for breaking said circuit when the arm is again retracted into the casing 1, thus effecting a saving in current.

Inner and outer operating members 11 and 12 respectively are operatively associated with the free ends of the innermost links 13 or arm 7, the outer ends of said operating members being pivoted at 14 and 15 respectively to a control lever 16, on opposite sides of the fulcrum 17 of said lever, the free end of the latter having a suitable foot pedal 16' whereby it may be depressed when required. This actuation of the lever 16, due to the relative locations of the pivots 14 and 15, 100

and the fulcrum 17, will move the outer operating member 12 upwardly and will simultaneously pull downwardly upon the inner operating member 11, thus projecting the arm 7. The members 11 and 12 are by preference constructed and attached to the links 13, as follows:

Collars 18 are received loosely in openings 19 in the free ends of the links 13 and 20 are pivoted to said links, both of said collars being mounted on the inner operating member 11, which is preferably in the form of a rod as shown. The lower collar 18 is slideable on the rod 11, whereas the upper 25 collar is movable bodily with said rod, the latter being provided with a nut or other suitable stop 20 positioned in contact with the upper end of said last named collar. The outermost operating member 12, 30 is in the form of a tubular rod slidably surrounding the rod 11 and bearing at its upper end against the lower collar 18, said member 12 being slideable in a tubular guide 35 which depends rigidly from the casing 1. The lower ends of the rods 11 and 12 are bent laterally into diverging relation and a portion of the lower end of said rod 12 is removed as will be clear from the drawings. This detail of construction is preferably employed, but it will be obvious that the portion of rod 12 which is connected to the lever 16 could well be constructed separately from the body of said rod and secured thereto in any preferred manner.

Employed in connection with the features of construction above described, is a coil spring 22 which surrounds the inner operating member 11 between the two collars 18, said spring being compressed when the collars are drawn together upon actuation of the foot pedal 17, said spring therefore exerting its tension to retract the several parts to their initial positions, when said pedal is released. The action of the spring, also 45 prevents excessive rattling of the device which would otherwise take place.

The device may be secured to the side of a vehicle by any appropriate means, but for illustrative purposes I have shown an arched bracket 23 secured to the lower side of the casing 1 and adapted to straddle the side of the vehicle as will be clear from Figs. 3 and 4. One of the improved devices will preferably be provided on each side of the machine and it will thus be clear that whenever required, either of the arms 7 may be projected to give notice that the vehicle intends to turn in one direction or the other, or will slacken its speed.

On account of the advantages derived from the specific construction shown and described, such construction constitutes the preferred form of the improved signal. I wish it understood, however, that within 65 the scope of the invention as claimed, nu-

merous minor changes may be made without sacrificing the principal advantages.

I claim:

1. A turning signal for vehicles comprising a lazy tong arm, a pair of operating members disposed one within the other and operatively associated with two of the links of said arm, and means for simultaneously moving said operating members in opposite directions to extend and retract said arm. 75

2. A turning signal for vehicles comprising a lazy tong arm, a pair of operating members operatively associated with two of the links of said arm, and a control lever operatively connected with said members on opposite sides of its fulcrum. 80

3. A turning signal for vehicles comprising a lazy tong arm, a pair of operating members disposed one within the other and operatively associated with two of the links of said arm, and a control lever operatively connected with said members on opposite sides of its fulcrum. 85

4. A turning signal for automobiles comprising a lazy tong signal arm, a tubular operating member operatively associated with one of the innermost links of said arm, a second operating member slideable through said tubular member and operatively associated with the other link at the inner end 95 of the arm, and means for shifting said members simultaneously in opposite directions.

5. A turning signal for vehicles comprising a lazy tong signal arm, a tubular operating member operatively associated with one of the links at the inner end of said arm, approximately half the width of said member, at the outer end thereof, being removed and the remaining portion of said 100 end being bent laterally, a second operating member slideable through said tubular member and operatively associated with the other link at the inner end of the arm, the outer end of said second member being also bent 105 laterally, and a control lever fulcrumed between said laterally bent ends of the operating members and pivoted to said ends.

6. A turning signal for vehicles comprising a lazy tong arm, a pair of collars to 115 which the innermost links of said arm are pivoted, an operating rod upon which said collars are mounted, one collar being slideable on said rod and the other movable bodily therewith, a spring between said collars, 120 a second operating rod operatively associated with the other collar, and means for simultaneously moving said rods in opposite directions.

7. A turning signal for vehicles, comprising a casing to be secured to the vehicle body, a signal arm, operating means for said arm positioned in said casing, the top of the latter having an opening through which 125 said operating means may be lubricated, a 130

hood positioned over said opening and hinged to the top of the casing, and a closure for the inner end of said casing, said closure being carried by said hood, whereby the two may be simultaneously opened and closed.

In testimony whereof I have hereunto set

my hand in the presence of two subscribing witnesses.

GOROICHI SAGARA.
